UNITED STATES PATENT OFFICE.

THOMAS J. FLAGG, OF NEW YORK, N. Y., ASSIGNOR TO FISK, CLARK & FLAGG, OF SAME PLACE.

DESIGN FOR A SCARF.

SPECIFICATION forming part of Design No. 15,295, dated August 19, 1884.

Application filed May 3, 1884. Term of patent 7 years.

To all whom it may concern:

Be it known that I, THOMAS J. FLAGG, of the city, county, and State of New York, have invented a new and original Design for a Scarf 5 for Men's Wear; and I do hereby declare that the following is a full and exact description thereof, reference being had to the accompanying drawing, and to the letters of reference marked thereon, making a part of this specification.

My design involves the configuration of the outer apron, S, of the scarf as its prominent feature; and it consists, as represented in the drawing, of an ogee curve, A B, merged at 15 its upper end in an inwardly-inclined line, A C, forming one edge of said apron, and of an inwardly-curved line, D E, joined to an inwardly-inclined upper line, E C, forming the opposite edge, the line E C being made to intersect the line A C at C upon one side of an imaginary straight line (see dotted line x x in the drawing) extending longitudinally through the center of the scarf, midway between the lines B A and D E. The form of the lower 20 end of the scarf, between the points D and B, is not an essential feature of the design, and may therefore be varied to present either a straight, a curved, or a broken or angular line, as D K B. The inwardly-curved lateral line D E corresponds in its curvature with the lower re-entrant curve of the ogee A B. It is 25 prolonged upwardly with an outward curve, E F, to form an ogee corresponding in length and form to the curve A B, and is merged at its upper end in an inwardly-inclined line, F G, corresponding in its length and inclination 30 to the line A C, the extreme upper end of these lines F G and A C being connected by a transverse line, G C, which, together with an inner line, G H, extending from the angle G 35 to intersect the line E C at the point H, where it is crossed by the imaginary central line, x x , serves to define the edges or outline of the inner apron, T, and center piece, U, and to 40 complete the outline of the entire scarf.

The design may be ornamented and relieved of stiffness and flatness in appearance by means of folds, plaits, or puffs K K, extending inward from the upper side lines, C A and F G, substantially as illustrated in the drawings. 50

I claim—

1. The design for a made-up scarf, herein shown and described, the same consisting of the outwardly-inclined line C A and ogee curve A B on one side, and the opposite lateral re-entrant curve D E and inwardly-inclined line E C, which, intersecting the first line at C, on the other side, completes the configuration of the outer apron of the scarf, in combination with the outline E F G H E, 60 which, coinciding at H E with a portion, C E, of the outline of the outer apron, and with the line G C, which, uniting the upper angles of the two aprons, defines the neck-line, and completes the configuration of the entire scarf. 65

2. The design for a made-up scarf, herein shown and described, the same consisting of the outwardly-inclined line C A and ogee curve A B, on one side, and the opposite lateral re-entrant curve D E, and inwardly-inclined line E C, which, intersecting the first line at C on the other side, completes the configuration of the outer apron of the scarf, the outline E F G H E, which, coinciding at H E 70 with a portion, C E, of the outline of the outer apron, defines the inner apron, the line G C, which, uniting the upper angles of the two aprons, defines the neck-line and completes the configuration of the entire scarf, and the 75 ornamentation K K.

In testimony whereof I have signed my name to this specification in the presence of two subscribing witnesses.

THOMAS J. FLAGG.
